J. R. BULLIS

CLAMP FOR TIE WIRES

Filed March 23, 1923

Patented Feb. 12, 1924.

1,483,213

UNITED STATES PATENT OFFICE.

JOHN R. BULLIS, OF WINSTON-SALEM, NORTH CAROLINA.

CLAMP FOR TIE WIRES.

Application filed March 23, 1923. Serial No. 627,206.

To all whom it may concern:

Be it known that I, JOHN R. BULLIS, a citizen of the United States, of Winston-Salem, in the county of Forsyth and State 5 of North Carolina, have invented certain new and useful Improvements in Clamps for Tie Wires; and I do hereby declare the following to be a full, clear, and exact description of the invention such as will enable others skilled in the art to which it 10 pertains to make and use the same.

My invention relates to concrete molds and particularly to means by which tie wires are anchored, and the object of my 15 invention is to provide a simple and efficient clamp for engaging the ends of wires employed in connection with forms used for walls, columns and floors, and one which is capable of being adjusted to effect a maximum 20 tension on the wire, the pull being evenly distributed, and maintained in adjusted position.

And a further object is to provide a clamp of this character which is especially 25 adapted for use with column forms, being capable of clamping a single wire passed around the column, thus effecting a saving in the cost of form construction.

In the drawings, Figure 1 is a perspective 30 view of a portion of a wall form showing my improved clamp attached to an upright. Figure 2 is a perspective view of a portion of a column form showing my improved 35 device clamping a single wire around the form. Figure 3 is a sectional view with the clamp used in connection with a form about an I-beam. Figure 4 is a view in front elevation.

In the use of my device with wall forms, 40 the tie wire A is passed from the upright B, see Fig. 1, through the sheathing on one side of the wall space to and through the complementary sheathing on the other side and then around the upright C and back in parallelism to the point of beginning where the two ends of the wire are engaged by the clamp. This clamp is preferably of cast metal and includes a circular base 1 having a neck 2 projecting therefrom and a head 3 45 preferably rectangular in cross section to provide gripping surfaces for a wrench or other tool. That portion of the head 3 immediately adjacent the neck is outwardly flared to act as a stop in the application of 50 the wrench and prevent contact between the latter and the tie wires. Extending trans-

versely through the neck 2 is an opening 4 to receive the ends of the tie wire, these ends being passed through the opening in opposite directions, as clearly shown in 60 Fig. 4.

In the use of my improved clamp, the tie wire is placed as hereinbefore described with its ends inserted in the opening of the clamp. A wrench is then applied to the head 3 and 65 the clamp turned so as to cause a binding of the wire about the wall uprights or the column form or the I-beam. This turning of the clamp, as will be apparent, winds the wire about the neck 2, the base 1 and flared 70 portion of the head acting as spool heads to retain the wire in position. When the desired tension has been got the clamp is anchored by driving nails 5 through the 75 openings 6 in the base 1.

As shown in Fig. 2, instead of extending a wire from one batten to that on the other side of the column form and back which requires a number of wires arranged at right angles to each other, to secure the necessary strength, I employ single wires 80 encircling the column form and secured at a single point by my clamp.

In Fig. 3 I have shown the use of my clamp in connection with covering an I-beam 85 with concrete. It has formerly been the custom to place the tie wire used with this class of work with its ends upstanding and to then bend them over the I-beam, but difficulty is encountered in bending the wires 90 about the flange of the beam because of the little space between the forms and the flange. My clamp permits the use of the tie wire in such a way as to avoid this trouble, the wires extending downwardly and being fastened 95 beneath the forms.

I claim as my invention:

1. A clamp for tie wires including a flat base for floating contact with a support, a part projecting from said base and formed 100 to receive the ends of a tie wire, and means for turning said clamp.

2. In combination with a support, of a clamp for tie wires about the support, including a flat base having floating contact with the support, a neck projecting outwardly from said base and formed to receive the ends of a tie wire, and a portion connected with said neck for turning said clamp. 105

3. A clamp for tie wires including a broad flat, floating base having means to permit 110

anchoring it against turning, a neck projecting from said base and having a transverse opening therein to receive the ends of a tie wire, an angular head on said neck for application of a tool to turn said clamp, and means for anchoring said clamp.

4. A clamp for tie wires including a flat floating base having openings to permit the passage of nails, a neck projecting from said base and having a transverse opening therethrough to receive the ends of a tie wire, an angular head on said neck for application of a tool to turn said clamp, that portion of

said head next adjacent said neck being flared.

5. In combination with a support and a tie therefor, of a clamp for the ends of the tie including a base floatingly engaging the support, and an integral part extending outwardly from the base and having the tie ends connected thereto and extending in opposite directions therefrom, said tie serving to hold the base seated on the support.

In testimony whereof I have signed this specification.

JOHN R. BULLIS.
